VACUUM-TUBE CIRCUITS AND THE LIKE AND METHOD OF CONTROLLING THE SAME

Application filed August 7, 1925. Serial No. 48,766.

This invention relates to improvements in vacuum tube circuits and the like, and the method of controlling the same, particularly with regard to circuits employed in radio communication.

In an electrical circuit including so-called negative resistance, it is well known that the phase relation between the voltage drop across the resistance and the current through the resistance is an important factor in determining whether or not the circuit will generate electrical oscillations.

The types of negative resistance devices commonly used in circuits for radio communication usually employ three electrode thermionic vacuum tubes, electric arc, or gaseous discharge devices. Since the three electrode vacuum tube is most commonly used in such circuits, the new method of oscillation control herein described, will refer particularly to the vacuum tube, although it is equally applicable to other types of negative resistance devices.

One object of this invention is to provide an improved method of controlling the tendency of the radio frequency tubes to oscillate in so-called radio frequency amplifying receivers.

Another object is to provide an improved method of controlling the oscillation of an electrical circuit including a negative resistance device.

Another object is to provide an improved method of controlling the oscillation of radio frequency vacuum tubes whereby the range of oscillation control is greatly increased as compared to existing methods.

Another object is to provide improved means whereby the inductance and the resistance in the plate circuit of a vacuum tube may be simultaneously varied for the purpose of controlling electrical oscillation of the circuit.

Another object is to provide an improved method of controlling the transfer of oscillating energy between successive stages of a vacuum tube radio frequency amplifier.

Other objects and novel features of this improved method and means for controlling vacuum tube circuits, will be apparent from

the following specifications and the accompanying drawings.

Embodiments of the invention are shown in the accompanying drawings in which:—

Figure 1 shows diagrammatically a radio receiving circuit employing a radio frequency amplifier tube and a detector tube with the new method of oscillation control. 55

Figure 2 shows diagrammatically a two stage radio frequency amplifier with the new 60 method of oscillation control and a detector.

Figure 3 shows a single stage radio frequency amplifier and detector with the new method of oscillation control applied to the radio frequency transformer, coupling the 65 detector to the amplifier.

Referring to Figure 1, the aerial 1 is coupled to the grid 2 of the first vacuum tube by means of the primary and secondary coils 3 and 4. The variable condenser 5 serves to 70 tune the grid circuit of the first tube. The plate circuit of this tube includes the inductive primary coil 6, the auxiliary coil 7, resistance 8 and a fixed condenser 9.

The secondary 10 of the above mentioned 75 radio frequency transformer is tuned by means of a variable condenser 11 and is connected through the grid condenser 12 and grid leak 13 to the grid 14 of the detector tube. The battery 15 maintains the plates 80 24 and 16 of the amplifier and detector tube respectively, at a positive potential with respect to the filaments 17 and 18. Battery 19 supplies through the resistance 20 a current 85 for heating the filaments 17 and 18. Telephone receivers 21 are connected to the plate circuit of the detector tube in the usual manner.

The operation of the circuit shown in Figure 1, is as follows:—Electrical oscillations 90 received upon the aerial are impressed upon the grid 2 in the usual manner. These oscillations cause corresponding variations in the electron flow from the filament 17 to the plate 24 of the vacuum tube. These variations in the plate current pass through coils 6 and 7 and through the condenser 9, back to the filament. A portion of the oscillating current is, however, diverted from the coil 7 via the resistance 8, the amount of such diversion 95 100

of current being dependent upon the position of the movable contact 22 on the resistance 8. The condenser 9 is of sufficient capacity to readily allow the passage of high frequency current so that very little of such current will pass through the battery 15. Direct current is supplied from the positive terminal of this battery through the resistance 8, inductance 7 and coil 6 to the plate 24 of the vacuum tube. The negative end of battery 15 is connected to the filament circuit in the usual manner.

The resistance 8 is preferably non-inductive and may have a value of the order of 15 200,000 ohms although the invention is not limited to this value. It is also preferably tapered so that its resistance per unit length decreases as the contact 22 moves toward the point 23. As the contact 22 approaches 23, 20 the portion of the resistance 8 in parallel with the coil 7 is progressively decreased, while the portion of resistance 8 in series with the battery 15 is progressively increased. Therefore, the inductive value of 25 coil 7, which is effective in the oscillating plate circuit, is progressively decreased, while the resistance in series with the voltage supply 15 is increased, thus decreasing the direct current voltage applied between the 30 plate 24 and the filament 17. It is, therefore, apparent that a movement of the contact 22 towards point 23 produces a simultaneous decrease in the inductance effective in the oscillating circuit and in the direct current 35 voltage applied between plate 24 and filament 17.

If the vacuum tube generates oscillations at a given frequency with the contact 22 at a position removed from 23, it will be found that as 22 moves toward 23, the generation of 40 oscillation at that frequency will gradually disappear. This disappearance of the generated oscillation is due to two factors. First, a decrease in effective inductance in 45 the oscillating plate circuit which changes the phase relation between the current through the vacuum tube and the voltage applied. Second, a decrease in applied voltage so that the so-called capacity feed-back 50 between the plate 24 and the grid 2 is decreased. It has been found that this simultaneous variation of the effective inductance in 55 the oscillating circuit and of the direct current voltage impressed upon this circuit produces a very smooth control of the oscillation of the tube over a wide range of frequencies.

Figure 2 shows the same general principle of oscillation control applied to a radio receiving circuit employing two stages of tuned 60 radio frequency amplification and a detector. The radio frequency amplifying tubes are shown respectively at 25 and 26 and the detector at 27. The grid circuits of these tubes 65 have inductive secondary coils 28, 29 and 30,

tuned by means of the variable condensers 31, 32 and 33, respectively.

The antenna coil is shown at 34 and the primary coils 35 and 36 are shown respectively in the plate circuits of the tubes 25 and 26. The filament battery 37 supplies heating current to each of the filaments of the vacuum tubes by means of conductors 38 and 39. The common conductor 40 connects together the plate coils 35 and 36.

The auxiliary coil 41 in series with the condenser 42, is connected between the common conductor 40 and the common filament circuit conductor 38. The battery 43 has its negative terminal connected to the conductor 38, and its positive terminal connected through the resistance 44 to the conductor 40. The variable contact 45, bearing on this resistance, is connected through the conductor 46 to the auxiliary coil 41. A somewhat lower voltage is tapped from the battery 43 by means of the conductor 47, which connects through the telephone receivers to the plate of the detector tube as shown.

The operation of the circuit of Figure 2 is 90 exactly similar to that of Figure 1, except that the effective inductance in the plate circuits of the two tubes 25 and 26 is simultaneously varied by changing the location of the contact 45 upon the resistance 44; and at 95 the same time a corresponding variation of the voltage impressed upon the plates of these tubes is effected. As the contact 45 is moved towards 40, the part of the resistance 44, electrically in parallel with the coil 41, is 100 progressively decreased, thereby decreasing the inductance of the coil 41 effective in the plate circuits of both the vacuum tubes 25 and 26. Coincidently with the above described decrease of effective inductance, there 105 is a corresponding increase of the resistance in series with the battery 43, thereby decreasing the voltage upon the plate circuits of both the tubes 25 and 26.

The principle of varying the inductance effective in the plate circuits and at the same time varying the voltage impressed upon these circuits, is shown applied to one and two tubes in Figure 1 and Figure 2, respectively, but may be equally well applied to any 115 desired number of radio frequency tubes.

Figure 3 shows a radio frequency amplifier tube 48 connected in cascade with a detector 49. The antenna coil 50 is coupled to a grid coil 51, which is tuned by means of a 120 variable condenser 52. The plate coil of the tube 48 has its windings in two sections 53 and 54. The conductors 55, 56, 57 and 58 connect the plate coil in series with the condenser 59 and across the filament and plate of the tube 48. The resistance 60 is connected by means of conductor 61 to a point on the plate coil intermediate the sections 53 and 54. The positive terminal of the battery 62 is connected to the resistance 60 by means of the 125

conductor 63. The negative terminal of this battery is connected to the common filament circuit as shown. The secondary coil 64 is inductively coupled to the composite plate coil above described and is tuned by means of the variable condenser 65. The contact 67 is movable upon the resistance 60 and is connected to the conductors 56 and 57 by means of a conductor 68. The telephone receiver 66 is connected to the plate of the detector tube 49 and to the battery 62 in the usual manner.

The operation of the circuit described in Figure 3, differs somewhat from the operation of those described in Figures 1 and 2, in that the mutual inductance of the plate coil and grid coil coupling successive vacuum tubes, is varied in addition to a variation of the self-induction of the plate coil. It is apparent from Figure 3 that the section 54 of the plate coil is shunted by a variable portion of the resistance 60. It is further apparent that as the resistance shunting the section 54 varies, the remainder of the resistance 60, which is in series with the battery 62, varies in inverse proportion. Therefore, as the resistance shunting 54 is decreased, the inductance effective in the plate circuit of the tube 48 is decreased, and at the same time the mutual inductance between the plate coil of the tube 48 and the grid coil 64 will also be decreased. Coincident with the above described decrease in self and mutual induction, there will be a corresponding decrease in the voltage effective between the plate and filament of tube 48. This is due to the increase of the part of resistance 60 in series with the battery 62.

It is well known that as the natural frequency to which the grid circuits of a multi-stage radio frequency amplifier are tuned is increased, the tendency for the radio frequency tubes to generate oscillations increases. It is further well known that as the above mentioned natural frequency decreases, the transfer of energy between successive stages through their mutual coupling also decreases. These factors all tend to facilitate the generation of oscillations in the amplifier circuits.

The method of control disclosed in Figure 3 governs the generation of oscillations by varying the self-induction in the plate coil of the amplifier tube, the mutual inductance of this coil with respect to the grid coil of the next tube, and the voltage impressed upon the plate of the amplifier. The simultaneous control of these factors by the circuit arrangement shown, provides a convenient method for governing the oscillation tendency of the radio frequency amplifier over a wide range of frequency.

Although the method of controlling oscillation is herein described as applied to the conventional three electrode vacuum tube, it is to be understood that other amplifying de-

vices having similar characteristics, may be employed without departing from the spirit or scope of this invention as set forth in the following claims.

I claim:

1. In an electrical circuit, including an electrical discharge device, a source of voltage in series with said device, an inductance coil in series with said device, an auxiliary inductance coil also in series with said device, a resistance having a variable portion in parallel with said second mentioned coil, the remainder of said resistance being in series with said voltage source, means for varying the portion of said resistance in parallel with said second mentioned coil and the portion in series with said voltage source, in inverse relation, whereby the inductance of said second coil effective in said circuit, and the voltage impressed upon said electrical discharge device may be simultaneously varied.

2. In an electrical circuit, including an electrical discharge device, a source of voltage in series with said device an inductance coil in series with said device, an auxiliary inductance coil also in series with said device, an electrical condenser in parallel with said device and both of said coils, a resistance having a variable portion in parallel with said second mentioned coil, the remainder of said resistance being in series with said voltage source, means for varying the portion of said resistance in parallel with said second mentioned coil and the portion in series with said voltage source, in inverse relation, whereby the inductance of said second coil effective in said circuit, and the voltage impressed upon said electrical discharge device may be simultaneously varied.

3. An electrical circuit, including a vacuum tube, an inductance coil in series with the plate of said tube, a second inductance coil in series with said first mentioned coil, an electrical condenser in parallel with said coils and said tube, a resistance in series with said first mentioned coil and a source of voltage, a common connection for said first and said second mentioned coils and said resistance, a contact movable upon said resistance for connecting the common terminal of said second mentioned coil and said condenser to a variable portion of said resistance, whereby the portion of said resistance in parallel with said second mentioned coil and the portion in series with said voltage source may be varied in inverse relation and a simultaneous variation of the inductance effective in said circuit and the voltage impressed on said circuit may be accomplished.

4. An electrical circuit including a three electrode vacuum tube, having a tuned grid circuit, a plate to filament circuit, including a main coil, an auxiliary coil and a condenser, a resistance having one terminal con-

5 nected to the common connection between
said coils, and another terminal connected
to a source of voltage, a variable contact
upon said resistance, said contact being con-
nected to the common terminal of said aux-
iliary coil and said condenser, whereby a
varying portion of said resistance may be
connected in parallel with said auxiliary
coil and an inversely varying portion of said
10 resistance may be connected in series with
said voltage source, for the purpose of con-
trolling the generation of oscillations by
said vacuum tube.

15 In testimony that I claim the foregoing
I have hereunto set my hand at Milwaukee,
in the county of Milwaukee and State of
Wisconsin.
